POSTING TRAY FOR LOOSE LEAF FILING SYSTEMS

Frederick Robert Sewell, Beckenham, England, assignor to Percy Jones (Twinlock) Limited, Beckenham, England

Application June 22, 1956, Serial No. 593,150

Claims priority, application Great Britain August 29, 1955

2 Claims. (Cl. 129—16)

This invention relates to improvements in posting trays for loose leaf filing, of the kind in which a horizontal surface is provided upon which a number of loose sheets are supported on their edges, with side rails extending upwardly from such horizontal surface to maintain the lateral edges of the filed sheets in register, and with end plates extending upwardly from said horizontal surface, one of which is disposed adjacent to one end of such surface and the other of which is movable along the length of such surface to any desired position of adjustment in which it can be locked, so as to retain in vertical position the filed sheets when not required for reference or entries thereon, the movable end plate being readily unlockable and movable to any desired position which may be convenient to permit of ready access to individual sheets among the pack of filed sheets held on the tray.

The present invention provides an improved construction and mounting of the side rails of such posting trays whereby the insertion or withdrawal of one or more sheets from the tray is facilitated, and an improved construction of the horizontal surface of the tray upon which the sheets to be filed are supported, and upon which are mounted the side rails and end plates.

According to the invention, each side rail is pivotally mounted at each end to the tray, and is held in a vertical or inclined position with respect thereto by catch means, the mounting of the ends of the rail including spring means normally maintaining the rails in engagement with said catches, the rail being manually movable against such spring means to permit disengagement of the rail from the catches so as to enable it to be swung from its normal position retaining the posted sheets from lateral movement to a position permitting such sheets to be withdrawn laterally from the tray without hindrance. As will be appreciated, ready movement of the side rails of the tray to such unlatched positions permits great ease and rapidity of side-wise or off-set posting or withdrawal of sheets onto or from the tray, as opposed to the relatively cumbersome and slow method employed in earlier posting trays, in which the siderails are not movable, or are movable only after operation of complicated release means, and which are therefore commonly employed in use for vertical posting as opposed to off-set posting of the filed sheets.

The construction of the tray itself, upon which the side rails and end plates are mounted, comprises in accordance with the invention an assembly of a central standard unit, in which is mounted the guide and locking means for the slidable end-plate normally provided with such trays, and a number of standard longitudinal sections adapted to be secured in pairs one on either side of the central unit to enable the tray to be built up from a stock of standard sections, e.g. of channel-form, to any desired width.

In accordance with a further feature of the invention, the mounting of the said side rails comprises means for

2

retaining the same in the normal locked sheet-retaining positions at any desired one of a number of alternative positions of inclination, from the vertical to a widely inclined position.

5 The combination with side rails capable of this variable inclination to the tray with the sectional build-up of the tray itself from standard stock units enables a posting tray to be constructed from a minimum number of standard stock parts in the factory to accommodate an extremely wide range of sheets of different widths, e.g. from sheets of 6" width to sheets of 14" width.

One constructional form of tray embodying the aforementioned aspects of the invention will hereinafter be described by way of example only, by reference to the accompanying drawings, in which

15 Figure 1 is a perspective view showing the preferred form of posting tray in accordance with the invention,

Figure 2 is a vertical sectional view of part of the horizontal supporting surface of the tray shown in Figure 1, on the line II—II of Figure 3,

20 Figure 3 is a plan view of such horizontal surface,

Figures 4 and 5 are detail views showing the end mounting of one side rail of the tray, in its locked and released positions respectively,

25 Figure 6 is a detail view of part of a side rail taken at right angles to Figure 4, and

Figures 7 and 8 are views similar to Figures 4 and 5, respectively, illustrating different positions of adjustment of the catch means forming part of the mounting of the

30 end of the side rail.

Referring to the drawings, the posting tray of the invention comprises a horizontal tray portion generally indicated at 1, built up from a central section 2 and two channel section units 3 which are similar to each other

35 in all respects, one on each side of such central section 2. As shown in the drawing, each channel section 3 has two longitudinal members 4 disposed within its two recesses 3a, the members 4 being spot-welded or otherwise secured in such recesses. The outer edge of each

40 unit 3 is formed with a flanged portion 5 and an inturned flange 6, and the inner end of each section 3 has a lateral extension 7.

Referring now to Figures 4 to 8 of the drawings, two side rails 9 are provided on the tray portion 1, each

45 rail being pivotally mounted by means of a slot 10 formed adjacent its lower end into which extends a pin

11 provided on a standard 12. A spring 13 mounted in such standard urges the end of the rail 9 upwardly to maintain a pin 14 thereon in engagement in a notch or

50 recess 15a formed in the end of an adjustably positioned arcuate locking bar 15 arranged in an arcuate guideway 12a provided in the standard 12. A locking screw 16, arranged on the arcuate locking bar 15, passes through a slot 12b provided in the guideway 12a, whereby the position

55 of the locking bar 15 can be adjusted and secured within the limits provided by the slot 12b.

The side rails 9 are thus normally retained by the effort of the springs 13 latched in the recesses 15a in the locking bars 15, which latter may be fixedly secured

60 either in the position shown in Figures 4 to 6, supporting the rails 9 in the vertical plane, or, as shown in Figure 8, in such a position as to support the rails 9 in planes inclined to the vertical. By this means, when the bars 15 have been brought to and secured in the positions

65 shown in Figure 8, the horizontal portions of the side rails 9 in their normal latched positions are displaced laterally from above the tray 1, thus enabling the tray to accommodate sheets of a width greater than that of the tray.

As will readily be seen, the desired angle of

70 inclination of the side rails can be obtained by suitable movement of the locking bars 15 as described above.

When it is desired to swing either or both of the side rails out of the way of the user, who wishes to withdraw or to insert a sheet or sheets in the tray, slight manual pressure upon the horizontal portions of the rails 9 causes the ends thereof to move downwardly against the effort of the springs 13, until the pins 14 of the rails are freed from engagement in the recesses in the locking bars. The rails can then be swung on the pins 11 to the position shown in Figure 7. To return the side rails 9 to their normal sheet-retaining positions, they are simply swung in the reverse direction until the pins 14 thereon engage the curved surfaces 15b of the ends of the locking bars 15, as shown in Figures 4 to 8, whereby the ends of the rails are caused to move downwardly against the springs 13, continuing swinging movement of the rails bringing the pins 14 into register with the recesses 15a in the locking bars, into which recesses they are then moved by the springs.

The combination of the sectional construction of the tray with the lateral adjustability of the side rails, renders the improved posting tray to be readily manufactured and used in standard sizes of constructional parts so as to accommodate substantially all the usual width of sheet normally required to be posted in filing trays of this kind.

I claim:

1. In a posting tray for loose leaf filing systems, a substantially horizontal rectangular tray having a standard at each corner thereof, a pair of generally U-shaped inverted side rails disposed along the opposite sides of said tray and having the lower ends of their legs pivotally attached to corresponding standards at the corners of said tray, said lower ends of the side rails being provided with elongate slots therein and each of said standards having a horizontal pin projecting therefrom received in such slots whereby to effect the pivotal mounting of the side rails on the standards, a locking bar carried by each of said standards above said pin and having a downwardly facing hooked end portion above said pins, a locking pin carried by each of said lower ends of the side rails cooperable with the hooked ends of said locking bars and receivable therewithin to retain said side rails in a substantially upright position along the sides of the tray, spring means engaging the lower ends of said side rails and normally urging the first mentioned pins to engage the bottoms of said elongate slots whereby to engage said locking pins in said hooked end portions of

the locking bars and permitting the locking bars to be depressed relative to the standards to withdraw the locking pins from the hooked end portions of the locking bars and permit outward swinging movement of said side rails, said locking bars being of arcuate configuration and being slidably received in arcuate channels in the standards, said arcuate locking bars and said arcuate channels being concentric with said horizontal pins, a stop pin fixed to each locking bar and each of said standards having an elongate slot therein receiving said stop pins limiting lateral movement of said locking bars whereby said side rails may assume an intermediate outwardly swung position without releasing said locking pins from said hooked end portions of the locking bars.

15 2. A posting tray for loose leaf filing systems comprising a horizontal sheet supporting tray, a pair of normally upstanding side rails, one of which is disposed along one side of the tray and the other of which is disposed along the opposite side of the tray, pivot means 20 fixed to said tray adjacent the lower extremities of said side rails, lower portions of said side rails provided with elongated apertures receiving said pivot means to permit swinging movement thereof between substantially vertical positions and substantially horizontal outwardly swung 25 positions, an elongate bar slidably carried by said tray on each side thereof above and adjacent the pivot means of its respective side rail and being movable back and forth in the direction of pivotal movement of said side rails, means on said tray limiting the sliding movement 30 of said bars, a notch on the lower edge of each bar, a pin on each side rail engageable in the notch of its corresponding bar and disposed at a point on each side rail spaced vertically of its pivotal connection to the tray, and spring means carried by said tray normally urging 35 each of said side rails in a direction to engage said pin in said notch.
